CLAIM

The ornamental design for a television receiver with graphical user interface, as shown and described.

DESCRIPTION

FIG. 1 is a front view of a television receiver with graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The dash-dash broken lines showing the television receiver form no part of the claimed design. The dash-dot broken lines define the bounds of the claim and form no part of the claimed design.

The appearance of the transitional image sequentially transitions between the images shown in FIGS. 1-6. The process or period in which one image transitions to another image forms no part of the claimed design.

1 Claim, 6 Drawing Sheets
